Primary Examiner — Susan Bennett Hattan*Assistant Examiner* — Leanne Was(74) *Attorney, Agent, or Firm* — Hinshaw & Culbertson LLP(57) **CLAIM**

The ornamental design for a reusable bottle stopper, as shown and described.

DESCRIPTION

FIG. 1 is a front perspective view of a reusable bottle stopper showing my new design in the opened position;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front perspective view thereof showing the reusable bottle stopper in the closed position;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines in the drawings illustrate portions of the bottle stopper that form no part of the claimed design. The lines on the surface of the bottle stopper indicate contour and not surface decoration. The areas shaded with dots in the drawings depict contrasting appearance.
